BOTTLE SEAL

Paul J. Marks, Rochester, N. Y.

Application December 23, 1935, Serial No. 55,704

9 Claims. (Cl. 215—38)

This invention relates to a combination bottle seal, opener and pryer and has for one of its objects to provide a new and improved construction for such a device.

5 Another object of this invention is to provide this device with an improved clamping mechanism.

Another object of this invention is to provide the clamping mechanism with antifriction rollers 10 which engage the bottle neck from opposite sides and permit the seal to easily slide on or off the neck and without marring or chipping the glass.

Another object of this invention is to provide 15 a bottle seal which may be placed on bottle necks of varying diameters and varying thicknesses of the bead surrounding the top of the bottle neck.

A further object of this invention is to so construct the bottle seal that the resilient sealing member thereof is drawn down onto the bottle 20 neck and partially forced into the opening thereof on the clamping of the seal to the neck of the bottle.

Another object of this invention is to provide the bottle seal with a movable handle for the 25 operation of the clamping mechanism and the placing and removing of the seal from the bottle.

A further object of this invention is to make the cap member of the seal movable on the clamping mechanism thereof to permit the cap 30 member to move down onto the bottle neck to hermetically seal the open end thereof while the clamping mechanism is firmly clamped to the bottle neck.

A further object of this invention is to combine 35 the bottle seal with a thermometer in such a manner that the temperature of the liquid sealed within the bottle by the seal is constantly indicated on a dial provided on the cap of the seal.

40 Another object of this invention is to provide the seal with a magnetic compass so that the clamping mechanism and cap of the seal provide a support for the compass.

All these and other objects and attendant 45 advantages of this invention will become more readily apparent from the detailed description thereof which follows, reference being had to the accompanying drawings in which

Figure 1 is a top plan view of the combination 50 bottle seal, opener and pryer.

Figure 2 is a side elevation thereof.

Figure 3 is a bottom plan view thereof.

Figure 4 is a side elevation thereof with the handle in its collapsed position.

55 Figure 5 is a vertical sectional view of the bot-

tle seal as it appears mounted on the neck of a bottle.

Figure 6 is a horizontal sectional view of the seal and bottle neck, the section being taken on the line 6—6 of Figure 5.

Figure 7 is a side elevation of a top of a bottle and a sectional view of the handle of the bottle seal in the position in which it is used as a bottle opener.

Figure 8 is a side elevation of a modified form 10 of the bottle seal.

Figure 9 is a top plan view of a modified form of the bottle seal with a thermometer incorporated therein.

Figure 10 is a vertical sectional view of the 15 bottle seal illustrated in Figure 9 and a portion of the bottle to which it is attached, the section being taken on the line 10—10 of Figure 9.

Figure 11 is a side elevation of the handle of the bottle seal and a sectional view of a can engaged 20 by the pryer illustrating the use of the pryer for the removal of the cover of the can.

In the several figures of the drawings like reference numerals indicate like parts.

The combined bottle seal, opener and pryer 25 forming the subject matter of my present invention is especially adapted for use on bottles having a neck with an annular bead around the top of the neck or an annular groove formed around the bottle neck at a short distance from the top 30 thereof. The clamping mechanism of my invention is adapted to engage the shoulder formed by the bead of the groove provided in the neck of the bottle and is firmly locked thereto while the cap is operated to seal the open end of the bot- 35 tle neck.

The opener of my invention is combined with a handle for the seal so that with the aid of my combined bottle seal and opener the original cap can be quickly removed from the bottle and 40 replaced by the seal to seal the bottle as tightly as it was originally sealed by the removed cap.

As illustrated in the various figures of the drawings the combined bottle seal, opener and pryer comprises the cap member 1 which is preferably formed of sheet metal with the bearing flanges 2, 2 bent down on opposite sides at one end, and with the bearing flanges 3, 3 bent down on opposite sides at the other end. The central portion of the cap member is enlarged and a narrow flange 4 embraces this enlarged central portion and connects the bearing flanges 2 and 3 on each side of the cap member. The bearing flanges 2, 2 are also connected at the end of the cap member 1 by the narrow flange 5 (Figures 55

3 and 6) which is curved inwardly thereof. This latter flange serves to brace the flanges 2, 2 to keep them from spreading. In the flanges 2, 2 are provided the elongated bearing slots 6, 6 and 5 in these bearings are adapted to rotate the pivot pins 7, 7 of the antifriction roller 8. A pair of torsion springs 9, 9 are mounted on the pin 10 to yieldingly engage the roller 8 and force its pivot pins 7, 7 to the inner end of the bearing slots 10 6, 6. In this way the roller 8 is made to yield and move laterally on the under side of the cap member when pressure is applied against it from the right hand side in the position of the seal illustrated in the figures of the drawings.

15 In the bearing flanges 3, 3 are provided the elongated bearing slots 11, 11 and in these bearings are mounted to rotate and roll back and forth the pivot pins 12, 12 of the antifriction roller 13. Also mounted between the bearing flanges 3, 3 is the fixed pivot pin 14 on which is mounted to swing the handle member 15 which operates the clamping mechanism of the seal and has incorporated therein the opener and pryer as will hereinafter be described. Surrounding 25 the pivoted end of the handle member 15 and forming integral parts thereof are the eccentric cams 16, 16 which, as illustrated in Figure 3, engage the pivot pins 12, 12 between the ends of the roller 13 and the bearing flanges 3, 3 so as 30 to force the roller to the left in the figures when the handle member 15 is moved from the position illustrated in Figure 2 to the position illustrated in Figure 5. The pivot pin 14 is located below the horizontal center line of the pivot pins 12, 12 35 and in the periphery of one or both of the eccentric cams 16 is provided a notch 17 which is arranged so that when the handle member is swung from a horizontal position slightly past the downwardly pointing vertical position and the 40 cams are rotated past their center line, the notch 17 presents itself to the pivot pins of the roller to have them engage thereinto to keep the handle from swinging back.

45 Substantially central of the top of the cap member 1 there is provided a circular depression which forms a boss 19 on the underside thereof. The sealing member of the seal which comprises the circular rubber disc 20 is located between this boss and the antifriction rollers 8 and 13 and is 50 thus removably held in place by the rollers on the underside of the cap member and its boss 19.

55 In placing the bottle seal on a bottle it is unfolded as illustrated in Figures 1 to 3 after which the cap member is positioned over the top of the neck of the bottle and is forced down over it to spread the antifriction rollers against the pressure of the spring or springs 9 to permit the annular bead of the bottle neck to pass thru between the rollers and contract on the underside 60 thereof to yieldingly clamp the bottle neck between the antifriction rollers on the underside of its annular bead or in the annular groove provided in the neck. The yielding mounting of the 65 roller 8 permits the bottle seal to be placed on bottle necks of varying diameters and varying thicknesses of the annular bead surrounding the top of the bottle necks, a feature which is extremely important in this invention because the 70 bottle necks and their beads vary considerably so that without this adjustable feature the seal would not operate efficiently on all bottles. The spring or springs 9 exert sufficient pressure against the roller 8 to firmly clamp the bottle neck between the rollers 8 and 13 and hold the

rubber sealing disc 20 slightly compressed against the open top of the neck to seal the bottle.

To increase the sealing effect of the rubber disc 20 and lock the bottle seal to the neck of the bottle, the handle member 15 of the bottle seal is swung from its dotted line position to the full line position illustrated in Figure 5. During this movement of the handle member the eccentric cams 16 thereof engage the pivot pins 12, 12 10 of the roller 13 and draw the cap member laterally over the top of the bottle neck. This movement of the cap member is permitted because of the elongated bearings 6 and 11 in which the pivot pins of the rollers 8 and 13 are mounted. In bottles in which the rollers 8 and 13 engage 15 the inclined shoulder on the under side of the annular bead without embracing the smallest diameter of the bottle neck below the bead, the pressure exerted by the eccentric cams 16 against the roller 13 forces this roller toward the roller 8 until both rollers embrace the smallest diameter of the bottle neck. During this clamping movement the rollers roll down the inclined shoulder on the underside of the annular bead and in doing so draw the cap member down onto 20 the top of the bottle neck to compress the sealing disc 20 and force the boss 19 along with a portion of the rubber sealing disc into the open end of the bottle neck as illustrated in Figure 5. For the operation of the bottle seal in this manner 25 the bearing slots 6 and 11 may extend horizontally in the cap member as illustrated in Figure 2.

30 However, in order to make the clamping effect of the bottle seal uniform on all bottles, the elongated bearing slots 6 and 11 are formed angularly into the flanges of the cap member so that when the cap member is moved laterally by the operation of the handle 15 it is simultaneously drawn 35 downwardly on top of the bottle neck to compress the sealing member 20 and to cause the boss 19 to force a portion of it into the open end of the bottle. By the use of the angular slots 6 and 11, as illustrated in Figure 4, the cap member is thus drawn onto the bottle neck whether 40 the clamping rollers originally engage the underside of the annular bead or are already located against the smallest diameter of the bottle neck 45 below the bead.

To prevent the seal from being twisted off by 50 a lateral pressure against the handle 15, the horizontal lugs 25 may be provided on the flanges 2 of the cap member as shown in Figures 2 and 4. These lugs are so arranged that when the cap member moves laterally on the locking movement of the handle 15, they are drawn against 55 the bottle neck below the annular bead thereof.

In Figure 8 I have illustrated a modification in which the roller 8 is held fixed in the cap member and the pivot pin 14 of the handle 15 is 60 mounted in elongated slots 36 and a torsion spring 37, carried by the cap, operates against the pivot pin 14 to yieldingly force the eccentric cams 16 against the pivot pins 12 of the roller 13. In this construction the yielding mounting of the 65 handle 15 takes care of the varying diameters of the bottle neck and the varying thicknesses of their annular bead.

70 The handle 15 is provided with an opening 26 and on one side of this opening is formed the wedge shaped projection 27. The opening 26 in the handle is dimensioned to have a portion of the edge of the cap 28 of a bottle project here thru as illustrated in Figure 7 so that the projection 27 can engage under the cap 28. By rais- 75

ing the bottle seal and its handle, the cap 28 may thus be readily and quickly pried off and removed from the bottle.

In order to make the handle 15 useful as an opener, as above described, it is necessary to make its handle portion longer. For this purpose suitable downwardly curved lugs 50 are formed at one end of the cap member 1 and these lugs engage the handle 15 when extended and hold the handle substantially in line with the cap as illustrated in Figures 7 and 12 to permit the use of the cap as an extension handle for the opener or pryer.

For the purpose of removing a cap which needs a prying instrument, the outer end of the handle 15 is provided with another wedge shaped projection 29. This lug can be readily forced between a container and its cap as illustrated in Figure 11 and then manipulated to force the cap off from the container.

In Figures 9 and 10 I have illustrated the bottle seal in a larger size for use on bottles such as milk bottles etc. The action in placing the seal on these bottles remains the same as above described. For the milk bottles the outer end of the handle 15 is provided with an elongated point 30 in place of the wedge shaped lug so that this point can be forced into the milk bottle cap and the cap pried out of the neck of the bottle.

As illustrated in Figures 9 and 10 the bottle seal may also be provided with a thermometer. For this purpose a dial 31 is provided in the central depression of the cap of the bottle seal and is covered by a suitable crystal 32. The indicator 33 of the thermometer is carried on a vertical shaft 34 which is operated by the heat responsive element located in the casing 35 which surrounds the shaft 34. The casing 35 depends from the cap of the seal so as to be located substantially centrally of the bottle neck when the bottle seal is attached thereto. The heat or cold responsive element of the thermometer is thus held suspended in the liquid of the bottle so that the temperature of the liquid within the bottle will be indicated at all times on the indicating dial of the bottle seal while the bottle remains sealed thereby.

I claim:

1. A bottle seal comprising a cap, a boss formed on the under side of said cap, a pair of antifriction rollers laterally movable on the under side of said cap, a sealing disc interposed between said rollers and said boss, yielding means operating against one of said antifriction rollers and cam means operating against the other of said antifriction rollers to clamp a bottle neck between them and hold said sealing disc compressed on top of the bottle neck with said boss forcing a portion of said sealing disc into the bottle neck.

2. A bottle seal comprising a cap, a pair of clamping rollers movably mounted on the under side of said cap, a handle mounted to swing on said cap, means operated by said handle against one of said rollers to cause said roller to move toward the other roller and clamp a bottle neck between them.

3. A bottle seal as set forth in claim 2 in which the means operated by said handle are yieldingly

mounted to compensate for variations in the diameters of bottle necks.

4. A bottle seal comprising a cap, bearing flanges depending from the sides of said cap, said bearing flanges having angular bearing slots provided therein, a pair of rollers mounted in said bearing slots, spring means carried by said cap and engaging one of said rollers and means carried by said cap and engaging the other of said rollers to cause said roller to move toward the 10 spring pressed roller.

5. A bottle seal comprising a cap, bearing flanges having angular bearing slots therein depending from the sides of said cap, a pair of rollers mounted in said bearing slots parallel to each other and adapted to move back and forth therein, resilient means carried by said cap and engaging one of said rollers to yieldingly hold it in place at one end of its bearing slots, a handle mounted to swing on said cap and a cam formed on said handle and engaging the other of said rollers to cause said second roller to move toward said spring pressed roller on the movement of said handle, said rollers and said bearing slots being spaced and arranged so as to clamp a bottle 25 neck between them and cause said cap to be drawn down onto the top of the bottle neck with the movement of said cam against its roller.

6. A sealing device for bottles, jars etc. comprising a cap, a yielding and a freely movable 30 clamping member carried by said cap and opposingly arranged for movement toward and away from each other; a cam mounted to rotate on said cap and engaging said freely movable clamping member and means provided on said cam and 35 adapted to engage said clamping member to lock said cam against movement.

7. A bottle or jar seal comprising a cap, a pair of roller clamping members spacedly and movably mounted on said cap, each of said roller clamping members having an annular segmental groove so as to partially encircle the bottle or jar neck on the engagement therewith and means carried by and movable on said cap and engaging one of said roller clamping members to cause said cap to move on said roller clamping members with the clamping members held against the bottle neck or jar.

8. A bottle seal comprising a cap, a spring pressed and a freely movable roller clamping member supported on said cap, an annular segmental groove in each of said roller clamping members adapted to have a bottle or jar engaged thereinto and means carried by said cap and movable independently thereof and engaging said 55 freely movable roller clamping member to cause said cap to move on said roller clamping members in forcing the freely movable roller clamping member against the bottle or jar.

9. A bottle seal comprising a cap, a pair of clamping members supported on said cap so as to be movable toward and away from each other, said clamping members being adapted to engage a bottle or jar between them and cam means movable on said cap to cause said clamping members to engage a bottle or jar between them and simultaneously force said cap onto the bottle or jar.

PAUL J. MARKS.
